UNITED STATES PATENT OFFICE.

WILLIAM PATTERSON, OF CONSTANTINE, MICHIGAN.

MACHINE FOR BORING HUBS.

Specification of Letters Patent No. 26,520, dated December 20, 1859.

To all whom it may concern:

Be it known that I, WILLIAM PATTERSON, of Constantine, in the county of St. Joseph and State of Michigan, have invented certain new and useful Improvements in Machines for Boring Hubs of Taper and other Forms for the Reception of Boxes, of which the following is a full, clear, and exact description, reference being had to the accompanying drawings, making part of this specification, in which—

Figure 1 represents an elevation of a machine embracing my improvements, and applied to a hub; Fig. 2 represents a longitudinal section of the machine as adjusted to bore tapering; Fig. 3 represents a similar section of the machine as adjusted for cutting out the interior of the hub (after it has been bored to receive the box or boxes) to cut off the inner ends of the spokes, and prevent them from resting and pressing unequally on the box, or on the exposed part of the axle, when short boxes are used; Fig. 4 represents a plan of the machine; Fig. 5 represents in perspective an inverted view of that portion of the machine that contains the spring seat for the swivel nut (detached from the cutter shaft) which allows the nut to yield, and with it, the cutter; when cutting shoulders in the hub for short journal boxes to fit against; Fig. 6 represents in perspective a view of the inner side of the circular plate that carries the swivel nut, and acts against the spring shown in Fig. 5; Fig. 7 represents in perspective one of the sliding ferrules for centering and securing the hub; and the nut which controls the ferrule and clamps it when set; detached from the screw shank which carries them. Fig. 8 represents in perspective the slide for adjusting the deflection of the cutter shaft, by its connection with the spring bar.

My improvement relates to the manner of cutting the shoulder on the interior of the hub, for short boxes, in a plane parallel to the end of the hub, while the cutter is carried and fed by an inclined screw shaft.

My improvement further relates to the combination and arrangement of an adjustable spring bar, with the cutter shaft, and adjusting slide for the purpose of cutting out the interior of the hub to cut off the ends of the spokes, and thereby prevent them from resting and pressing unequally on the box; or from coming in contact with the

exposed part of the axle when the hub is fitted with short boxes.

In the drawing A, and B, represent two circular metallic boxes, between which the hub is centered and secured. They are connected together by means of a screw shaft which carries the cutter by which the interior of the hub is cut to the required taper and form. One of these boxes A, I denominate the adjusting box; the other B, the yielding swivel-nut box. The first of these boxes consists of a ring having an annular seat (a) and shoulder (b), as shown in Figs. 2 and 3. To this annular seat a slotted center disk (C) is fitted so as to revolve truly and steadily within the ring—having its center of motion coincident with that of the swivel nut.

The center disk (C) projects beyond the supporting ring a sufficient distance to form a pulley (c) by which the cutter shaft may be driven by band. The outer face of this disk is fitted with a slide (D) having a slot (d) corresponding to that in the center disk, through both of which, the cutter shaft passes, and is attached to the slide, by a steel spring bar, to be hereafter described. The center disk is held in its seat by two screws (e) passing through the fixed ring into an annular groove in the center disk.

The box B, has its side adjacent to the hub closed (except an opening sufficient for the shaft to pass through) by a fixed plate; the opposite side is closed by a circular plate (f) fitted into the box against a strong spring, which tends constantly to press the plate from the cutter—but which is restrained from being pressed out of the box by two screws, the heads (g g) of which, overlap projections from the plate which fit into grooves on the interior of the box, whereby the plate can yield in the direction of the length of the cutter shaft, but cannot rotate with said shaft for a purpose to be hereafter described. This circular plate (f) has a projection (h) on its inner side with an annular opening extending through the plate, into which a nut (i) is fitted through which the screw shaft passes. The nut is held in position by two screws (i'), passing through the projection (h) and into the opposite sides of the nut, on which the latter may rock to accommodate the obliquity of the shaft, as it revolves with the cutter.

The circular boxes A, and B, are pro-

vided with radial shanks (E), (in this instance three) placed equidistant from each other, and have screw threads cut thereon as shown in Figs. 3 and 5. Each screw shank is furnished with a ferrule (F) so as to slide over and on the screw threads; and each ferrule is made with a projection (F') at its inner end of such shape as to fit against the end and side of the hub when the latter is centered and clamped. Each ferrule has a nut (G) connected with it, and fitted to the threads of the screw shank. The nut (G) is connected to the outer end of the ferrule by means of a stem (j) extending from the interior of the ferrule to the outer end of the nut and bent so as to embrace the end of said nut, and lock it to the ferrule, as shown in Figs. 2 and 3, so that the nut is free to turn, and its action on the screw, is not interrupted, while, by means of a longitudinal groove or channel (k) in the shank, into which the stem fits, the ferrule is prevented from turning with the nut, but is free to be moved on the shank toward or from the hub, according as the nut is turned to the right or left, by the handles with which it is provided. By this arrangement it will be seen, that the hub holders can be managed with ease and facility in centering, clamping and unclamping the hub, as the turning of the nut controls and adjusts the movements of the clamping ferrules.

The slide (D) is carried by, and rotates with the center disk; and its adjustment is effected by means of a thumb screw (H) passing through a projection on the center disk, and has its end swiveled into a similar projection on the slide. The cutter shaft passes through the center disk and slide without being directly connected to either; this is for a purpose to be presently described. The shaft however is indirectly connected to the slide (D) by means of a steel spring bar (I) attached to the shaft permanently at one end and by a set screw (m) at the other. Its edges are beveled, and the opening in the slide through which it passes is of a corresponding shape as shown in Fig. 4, and the bar, is therefore free to move longitudinally with the shaft, as well as transversely with the slide, but it has no transverse adjustment in relation to the center of motion independent of the slide.

A portion of the cutter shaft has a screw thread (J) cut upon it—the other part (J') being square in its cross section. At the junction of the screw with the square portion, the cutter (K) is screwed, by having its shank fitted into a mortise so that its cutting edge may be adjusted nearer to, or farther from the center of the shaft and secured by a screw.

The screw (J) on the shaft is of a length greater than that of the hub and works into

the threads of the center nut (i); while the square portion of the shaft passes through the center disk (C) and slide (D), and is of a length sufficient to allow the cutter to pass entirely through the hub.

A collar (L) is fitted to the shaft above the center disk so that it may be adjusted thereon and clamped by a set screw at the proper distance from the cutter, for the purpose of arresting the progress of the cutter, by coming in contact with the center disk. This collar is only used when the hub is to be tapered and formed with shoulders to receive short boxes; and as the cutter traces a spiral line corresponding to the screw thread, it is plain that the shoulder will be the counterpart of the screw, and the object of mounting the swivel nut in the yielding plate is to remedy this evil by terminating the shoulder in a plane parallel with the end of the hub, so that the box may fit flush against the shoulder. An inspection of the drawings will show how this is accomplished. When the collar (L), by the progress of the cutter in the hub, comes in contact with the center disk, the longitudinal movement of the cutter will cease, and thus determine the shoulder. At this point, in the operation, the shoulder is left in a spiral line, and the screw shaft can feed the cutter no farther; therefore, by turning the shaft two or three more revolutions, the cutter will move in a plane parallel to the end of the hub—the screw shaft causing the swivel nut to approach the cutter against the tension of the spring sufficient distance to allow the cutter to make the shoulder true.

The spring (M) against which the swivel nut acts is coiled within the box (B), and tends constantly to press the swivel nut outward. It is strong enough to oppose the resistance offered to the cutter, as the latter is fed by the screw, through the hub, but is compressed when the collar (L) is arrested,—thus by a simple and effectual arrangement of a fixed stop and yielding center nut, I am enabled to feed the cutter by an inclined screw shaft, and form a true shoulder during the operation and without risk of stripping the threads from the shaft.

Having described the steel spring bar (I) and its attachment to the slide (D), I will now state the object of this arrangement. The hub is fitted with the spokes, before it is bored to receive the box or boxes, and the ends of the spokes protrude through into the bore. When the hub is tapered from end to end, the spokes are cut off flush with the interior of the hub, and when the box is secured in place, the wheel finished and used, the ends of the spokes will work through and press unequally on the box, which is very objectionable. When short boxes are used, the ends of the spokes will often work

through and come in contact with the exposed part of the axle. It is the object of one branch of my improvements to remedy these difficulties by cutting the interior of the hub concave, after it has been bored for the box, as will be seen by reference to Fig. 3. An adjusting screw (*n*) passes through the shaft and is swiveled into the steel bar (*I*) near the middle of its length. As the shaft is not connected with the slide, it is evident that by turning the screw (*n*) to the right the spring bar (*I*) will bend, so as to allow the shaft to be separated from it—the opening in the slide being for that purpose. Now as the spring bar is fixed in relation to the slide, the threads of the screw acting on the shaft, will consequently cause the shaft to be deflected farther from the center of motion, thereby giving the required bend to the bar outward at its middle, while its ends are attached to the shaft. The spring bar thus adjusted, acts as a guide to the cutter which projects from the opposite side of the shaft, causing it to trace a line the reverse of the bend of the spring bar, thus boring the interior of the hub concave and cutting off the ends of the spokes a sufficient distance to prevent them ever resting on or coming in contact with the box, or the exposed part of the axle. The inner end of the bar may also be adjusted in connection with the middle screw; if necessary, to give the spring bar the shape to produce the required concavity in the hub.

The machine is mounted upon a suitable frame or bench; and the cutter shaft may be operated by a belt passing around the pulley of the center disk, or by means of a crank handle on the end of the square part of the shaft.

I deem it unnecessary to describe more fully the operation of the machine, as it will be sufficiently understood by reference to the drawings and foregoing description.

In cutting and tapering the hub for the reception of short boxes, it will be necessary to reverse the hub to cut each end to the proper depth and diameter; but in boring the taper from end to end of the hub, it is only necessary to make such adjustments as to cut the interior of the hub of the proper taper and diameter to receive the box; and by the aid of a scale on the center disk and a pointer on the slide, these adjustments can be easily determined by any competent mechanic.

Having described my improvements, I claim—

1. In combination with the swivel nut (*i*) having a yielding or spring seat (*M*), the adjustable collar (*L*) and cutter shaft for causing the cutter to form a shoulder in the hub in a plane parallel to the end of the hub, while the cutter is carried and fed by an inclined screw shaft, as herein described.

2. I also claim the combination of the guiding spring bar (*I*) and its adjusting screws (*m n*) with the slide (*D*), center disk (*C*) and cutter shaft, for the purpose of boring out the interior of the hub and cutting off the ends of the spokes and thereby prevent the latter from resting and pressing unequally on the box, or on the exposed part of the axle, as herein described.

In testimony whereof, I have hereunto subscribed my name.

WILLIAM PATTERSON.
